By his Attorney *James J. Sheehan*

UNITED STATES PATENT OFFICE.

JAMES W. HOSEA, OF HUTCHINSON, KANSAS.

SASH-FASTENER.

SPECIFICATION forming part of Letters Patent No. 417,388, dated December 17, 1889.

Application filed September 14, 1889. Serial No. 323,936. (No model.)

To all whom it may concern:

Be it known that I, JAMES W. HOSEA, a citizen of the United States, residing at Hutchinson, in the county of Reno and State 5 of Kansas, have invented certain new and useful Improvements in Sash-Holders; and I do declare the following to be a full, clear, and exact description of the invention, such as will enable others skilled in the art to which 10 it appertains to make and use the same.

This invention relates to sash-locks and sash-holders for windows; and it consists in the construction and novel combination of parts, as hereinafter fully described and 15 claimed.

In the drawings, Figure 1 is a front elevation with a portion of the window-frame and a portion of the upper rail of the lower window-sash broken away to show the locks 20 and rack. Fig. 2 is a detail view of the lower bolt and slotted guard-plate. Fig. 3 is a detail view of the upper bolt and its slotted guard-plate; and Fig. 4 is a detail perspective view of the keeper-rack with which 25 the sliding bolts engage when the parts are properly arranged to lock and hold the window-sashes in either the desired open positions, or in the closed position, as may be desirable or necessary.

Referring by letter to the accompanying drawings, A designates the window-frame, which is of the usual or ordinary construction, with the exception that on one side the upper half of the parting-strip is removed 30 or cut away, and is replaced by a metal rack B, having rectangular teeth C, separated by rectangular spaces or keeper-seats D, extending laterally across the exposed or projecting inner face.

The upper cross-rail or meeting-rail E of the lower window-sash is recessed in the upper face at one end in the outer side of the rail at F, and in the recess F is secured, by a screw or screws or in any suitable manner, 40 a slotted face-plate G, which covers a sliding bolt H, preferably rectangular in outline in cross-section, said sliding bolt H being adapted to have a longitudinal reciprocating movement in its seat, when operated by 45 its finger-piece I, to cause it to be moved into engagement with the teeth of the parting-strip B, to lock the sash in engagement therewith, or to permit the sash to be moved up or down to the required or desired posi-

tion, as necessity or convenience may suggest, and afterward locked in position by pushing or moving the sliding bolt into its appropriate notch or recess in the rack or parting-strip.

The upper sash K is recessed in its vertical rail L, the inner face of which bears against the outer face of the rack or parting-strip B. In this recess M is placed an angularly-bent sliding bolt N, the locking-arm P of which projects inwardly, and is 60 adapted to be engaged with the notched parting-strip or rack by moving it into either one of the rack-seats to lock or hold the window-sash in the required position, or to be withdrawn by its finger-piece and permitted to remain out of engagement therewith, so that the sash may be raised or lowered. The location of these locks and 65 holders being on the inside of the sashes prevents access to them from the outside, unless the window-glass be broken, so that they afford safe locking means for the sashes, either in the open or closed positions, so that the room in which a window provided with them is located may be properly 70 ventilated without permitting the entrance of burglars or others to the room unannounced.

The construction herein employed renders sash cords and weights unnecessary; 75 but the cords and weights may be used in connection with these devices, and where cords and weights are already in use they may be left in place, and my improved parting-strip and sliding bolts may be added.

Having thus fully described my invention, what I claim as new, and desire to secure by Letters Patent, is—

The rack B, taking the place of the upper part of the parting-strip on one side of the window-frame, in combination with the upper sash K, the plate having the recess M, and secured to the rail of the sash engaging the outer side of said rack, the angular bolt N, having the locking-arm P projecting 85 inwardly so as to engage the teeth of the rack, substantially as specified.

In testimony whereof I affix my signature in presence of two witnesses.

JAMES W. HOSEA.
